UNITED STATES PATENT OFFICE.

AUGUST W. L. HARTBAUER, OF CHICAGO, ILLINOIS, ASSIGNOR TO AMERICAN CAR AND FOUNDRY COMPANY, OF ST. LOUIS, MISSOURI, A CORPORATION OF NEW JERSEY.

DECK-SASH PIVOT AND LATCH.

1,074,117.

Specification of Letters Patent. Patented Sept. 30, 1913.

Application filed October 1, 1912. Serial No. 723,440.

To all whom it may concern:

Be it known that I, AUGUST W. L. HARTBAUER, a citizen of the United States, residing at Chicago, Illinois, have invented a certain new and useful Improvement in Deck-Sash Pivots and Latches, of which the following is a full, clear, and exact description, such as will enable others skilled in the art to which it appertains to make and use 10 the same, reference being had to the accompanying drawings, forming part of this specification, in which—

Figure 1 is a perspective view of a portion of a railway car deck showing a deck 15 sash or window, the same being provided with my improved pivoting and latching device. Fig. 2 is an enlarged vertical section taken approximately on the line 2—2 of Fig. 1. Fig. 3 is a front elevational view of 20 the parts seen looking in the direction indicated by the arrow 3 in Fig. 2. Fig. 4 is a detail sectional view of a modified form of the latch.

This invention relates generally to the 25 sashes or windows in the decks of railway passenger cars, and more particularly to the pivoting and latching means for said sashes.

It is essential for ventilation purposes 30 that the deck sash be arranged so as to be readily shifted into an open position, and to this end pairs of hinge plates are arranged on the ends of the deck sash and upon the adjacent deck posts, and in order 35 to permit the deck sash to be readily opened and held at different points in open position, I propose to provide notched quadrant plates on the deck posts, and to arrange spring-held pawls on brackets carried by the 40 sash, the points of which pawls are adapted to engage in the notches in the quadrant plates, thereby firmly holding the deck sash in its adjusted position.

One of the principal objects of my invention 45 is to provide a quadrant plate having notches on both side faces along one edge, and thus the quadrant plate is interchangeable in that it can be used at either end of the deck sash, and such construction doing 50 away with the necessity of providing right and left-hand quadrant plates.

A further object of my invention is to provide a simple, inexpensive deck sash pivot and latch which can be easily applied

for use, and which permits the sash to be 55 readily shifted from one position to another.

To the above purposes my invention consists in certain novel features of construction and arrangement of parts hereinafter more fully described and claimed. 60

Referring by numerals to the accompanying drawings: 1 designates the deck roof, 2 the deck posts and 3 the deck sash which is arranged in the usual manner between the posts 2. Fixed in any suitable manner to the 65 lower portions of the posts 2 and projecting outwardly therefrom are quadrant plates 4, and formed on or fixed to the side faces of these plates along the curved edges thereof are ribs or flanges 5 in which are formed 70 notches 6, the same being suitably spaced apart. Fixed to the side portions of the deck sash 3 and projecting outwardly therefrom at points immediately adjacent to the plates 4 are brackets 7, the outer ends of 75 which are provided with vertically disposed plates 8. Formed on each plate is a pair of ears 9, and pivotally mounted upon a pin 10 seated in said ears is a pawl 11 provided on its upper end with a tooth 12 which is 80 adapted to engage in the notches 6. The upper portion of the plate 8 is provided with an opening 13 to accommodate the tooth 12. Formed integral with the lower portion of the pawl 11 is a depending lip 14, and interposed between this lip and the lower portion of said plate 8 is a small compression 85 spring 15. Formed on or fixed to the bracket 7 is an outwardly projecting pin or trunnion 16 which is mounted for rotation 90 in a suitable bearing formed in the corresponding plate 4.

When the deck sash is closed the teeth 12 on the pawls 11 engage in a corresponding pair of the notches 6 and said pawls maintain their positions by the power stored in the springs 15. When it is desired to open the deck sash the upper portion on the inside thereof is engaged and pulled inwardly with sufficient power to overcome the 100 resistance offered by the springs 15, and as a result, the teeth 12 ride out of the notches in which they have been engaged, and said teeth ride along the surface of the ribs or flanges 5 until they drop into the succeeding 105 pairs of notches, and thus the deck sash will be firmly held in open position. The spaced notches 6 which are engaged by the teeth

or points of the pawls 11 provide means whereby the deck sash may be held open at different degrees.

In the modified construction shown in 5 Fig. 4 a torsionally bent spring 15^a is positioned on the pivot pin 10, one end of which spring bears against the plate 8 and the opposite end against the depending lip 14.

A deck sash pivot and latch of my improved 10 construction is comparatively simple, is composed of few parts which can be easily and cheaply manufactured and assembled, permits the deck sash to be readily closed or swung into open position and effectively holds said sash after movement in 15 either direction.

By forming notches on both side faces of the quadrant plates the same can be interchangeably used at the ends of the sash, thus 20 doing away with the necessity of forming said plates in rights and lefts.

It will be readily understood that minor changes in the size, form and construction 25 of the various parts of my improved deck sash pivot and latch can be made and substituted for those herein shown and described without departing from the spirit of my invention, the scope of which is set forth in the appended claims.

30 I claim:

1. The combination with a deck sash and deck post, of a member fixed to the deck post, which member is provided with a series

of notches in its side face, of a bracket fixed to the deck sash and pivotally connected to 35 the first mentioned member, a plate on the outer end of the bracket, which plate is provided with an opening, and a spring-pressed pawl pivotally mounted on the plate, the point of which pawl passes through the 40 opening in said plate to engage the notches in the side face of the first mentioned member.

2. The combination with a deck sash and deck posts, of interchangeable quadrant 45 plates fixed to the deck posts, which quadrant plates are provided with notches in their side faces, brackets fixed to the deck sash adjacent to the quadrant plates, trunnions on said brackets which operate in 50 bearings in the quadrant plates, plates integral with the brackets, which plates are provided with openings, and spring-pressed restraining pawls on said last mentioned plates, the points of which pawls pass 55 through the openings in said plates to engage the notches in the quadrant plates for holding the deck sash in adjusted position.

In testimony whereof I hereunto affix my signature in the presence of two witnesses, 60 this 18th day of September, 1912.

AUGUST W. L. HARTBAUER.
